UNITED STATES PATENT OFFICE.

GEORGE LIGOWSKY AND AMOS WOEGER, OF CINCINNATI, OHIO, ASSIGNEES
OF ONE-THIRD OF THEIR RIGHT TO DAVID FOLZ, OF SAME PLACE.

TARGET-BALL.

SPECIFICATION forming part of Letters Patent No. 225,621, dated March 16, 1880.

Application filed September 5, 1879.

To all whom it may concern:

Be it known that we, GEORGE LIGOWSKY and AMOS WOEGER, both of Cincinnati, Hamilton county, Ohio, have invented a new and useful Explosive Target-Ball, of which the following is a specification.

The object of our invention is to furnish a target-ball that will afford indisputable evidence of being struck the instant a shot penetrates the same, and which, at the same time, will be perfectly safe to handle, and will be free from the objections urged against target-balls as generally constructed.

We accomplish this result by making the ball of a shell of clay or other light plastic material, which shell is coated internally with any fulminate that will readily ignite and explode the ball the moment the latter is penetrated with a shot, the cloud of vapor or gas resulting from the explosion affording ocular proof to the spectators that a hit has been fairly made.

The preferred method of constructing this ball is by joining two hollow hemispherical shells together so as to produce a complete sphere, the junction of these two members being further strengthened by means of a band glued or cemented around them, as hereinafter more fully described.

In the annexed drawings, Figure 1 is a vertical section of a complete target-ball embodying our improvements. Fig. 2 is a perspective view of the two shells of which said ball is composed.

A B represent two hemispherical shells, of clay or any other material or composition of materials that is light and cheap and is capable of being readily molded or otherwise fashioned to the desired shape. These shells are coated internally with any suitable fulminate, C, that will ignite or explode the instant the ball is shattered with a shot or other projectile.

The margins of these shells are glued or cemented or otherwise joined together, after which act a zone or band, D, is glued around the complete ball, so as to strengthen the same and conceal said joint, as seen in Fig. 1. This band may be composed of cloth or thick paper or other material, and may be ornamented to add to the appearance of the ball.

Furthermore, our ball may constitute part of a rocket, so as to ascend as soon as the latter is fired off, or it may be projected from a trap in the usual manner; but in either case the concussion or jar attending the start of the ball, or the handling or transportation of the same, will not cause an explosion, because the fulminate is internal. As soon, however, as a shot fractures the ball and drives the fragments of the latter inwardly the fulminate instantly ignites, thereby generating a gas or vapor whose expansion insures the destruction of the target.

At the moment of contact a slight flash is emitted, which is immediately followed by a dense cloud of smoke or gas, that affords the most convincing proof of the target having been fairly struck by the shot or other projectile discharged at the same.

As this fragile ball is more readily fractured than is a glass one, it is evident the use of the same lessens the charge of powder, and thus reduces the labor of the sportsman. Furthermore, the clay or earthenware ball will not cause the shot to glance aside and leave the target unbroken; neither will the fragments of the ball injure a lawn or grass-plot, as the small particles of clay are soon decomposed by the elements. In addition to these advantages the balls are of uniform weight and size, and are capable of being readily painted, varnished, or glazed, which external coating may render the targets water-proof.

While preferring the ball herein shown, we wish it distinctly understood that our invention is not limited to any special shape, or to any number of component parts, as the target may be elliptical, oval, spheroidal, or any other desired form. Finally, the right is reserved of embodying in a future application the compound shell and rocket referred to in this specification.

We claim as our invention—

1. A hollow target ball or shell composed of a suitable fragile material or materials, and coated internally with a fulminate that will explode the ball as soon as the latter is penetrated with a shot or other projectile, substantially as herein described and set forth.

2. A target ball or shell composed of a suit-

100

able plastic material and coated internally with a suitable fulminate, for the purpose described.

3. A target-ball composed of two shells of plastic material united together and coated internally with a suitable fulminate, as and for the purpose set forth.

4. A target-ball composed of two shells, A, B, of plastic material united together and surrounded with a band, D, said shells being

coated internally with a suitable fulminate, C, as and for the purpose set forth.

In testimony of which invention we hereunto set our hands.

GEORGE LIGOWSKY.
AMOS WOEGER.
